FREQUENCY MODULATION APPARATUS

William F. Goetter, Schenectady, N. Y., assignor
to General Electric Company, a corporation of
New York

Application May 28, 1942, Serial No. 444,843

9 Claims. (Cl. 179—171.5)

My invention relates to frequency modulation apparatus, and more particularly to that type of such apparatus commonly termed phase modulation apparatus.

In apparatus, which is utilized to modulate the phase of a carrier wave in accordance with a modulating potential, it is desired that such phase be modulated in linear relationship to the modulating potential. That type of apparatus which modulates the phase directly, as by phase splitting of the carrier wave, and is arranged to modulate the phase of the carrier wave the same amount for the same modulating potential of any frequency, should modulate the phase of the carrier wave in linear relationship to the modulating potential intensity at any modulating frequency. If such linear relationship does not obtain, when the modulated carrier wave is demodulated in any desired fashion, harmonics and cross-modulation products of such harmonics of the modulation potential are obtained. To avoid obtaining such harmonics and cross-modulation products of harmonics, it is necessary to preserve such linear relationship.

It is accordingly an object of my invention to provide a new and improved apparatus whereby the phase of a carrier wave is modulated in linear relationship to the intensity of a modulating potential.

A similar apparatus for improving the linearity of the relationship between modulation of the phase of a carrier wave and the modulating potential is disclosed and claimed in the copending application for Letters Patent of the United States, S. N. 440,172, filed April 23, 1942, of George M. Brown, Frequency modulation system, assigned to the same assignee as the present application. In this copending application a three-channel phase modulation system is utilized, in which three components of the carrier wave are generated. Two of these components are of opposite phase, and the third differs by a quarter cycle from each of the other two components. The two oppositely phased components are modulated oppositely in intensity in response to modulating potential, and the third component is reduced in intensity, in response to increases in intensity of either polarity of the modulating potential, an amount such that the phase of the resultant of the three components of the carrier wave is shifted by an amount substantially proportional to the intensity of the modulating potential.

It is a specific object of my invention to provide a new and improved apparatus and method

for reducing the intensity of such third component in such a way as to increase the linearity of the relationship between phase shift of the carrier wave and intensity of the modulating potential.

In such a multiple channel phase modulation system, the change in frequency of the carrier wave produced by its change in phase in response to modulating potentials is very small. 5 It is necessary to multiply the frequency of the carrier wave many times through suitable frequency multiplying amplifiers which simultaneously increase the frequency change of the carrier wave, to obtain a change in frequency of 10 the radiated carrier wave reasonably large with respect to the frequency of the modulating potential. It is well known that the modulation of the frequency of the radiated carrier waves should be large with respect to the frequency 15 of the modulating potential to obtain noise-free signal transmission.

When a very large amount of frequency multiplication is thus used, very small random voltages in circuits preceding those utilized for such 20 frequency multiplication produce substantial frequency changes in the radiated carrier wave. It is accordingly another object of my invention to reduce the amount of frequency multiplication necessary in a phase modulation system and 25 thereby reduce the amount of random frequency shift of the carrier wave caused by small voltages, commonly called noise voltages, by providing a new and improved apparatus and method for modulating the phase of a carrier 30 wave to a larger degree while retaining high linearity in the relationship between phase shift of the carrier wave and the intensity of the modulating potential.

The features of my invention which I believe 35 to be novel are set forth with particularity in the appended claims. My invention itself, both as to its organization and manner of operation, together with further objects and advantages thereof may best be understood by reference to 40 the following description taken in connection with the accompanying drawings in which Fig. 1 illustrates one embodiment of my invention; Figs. 2 through 7 are vector diagrams and graphs representing certain characteristics of the apparatus of Fig. 1; and Figs. 8, 9 and 10 illustrate modified versions of a certain portion of 45 the apparatus of Fig. 1.

In that form of my invention which is illustrated in Fig. 1, a high frequency carrier wave 50 from the source 10 is transmitted in different

phases through three different channels including the electron discharge devices 11, 12 and 13, and after recombination through suitable frequency multipliers and power amplifiers 14 to be radiated from an antenna 15. Those three components of the carrier wave from the source 10 transmitted through the devices 11 and 13 are suitably modulated in intensity in accordance with signals from a microphone 16 as described hereinafter.

The apparatus utilized to divide the high frequency carrier wave from the source 10 into three components, two of which are in opposite phase and the third of which is different in phase by a quarter cycle from the first two, includes a pair of tuned circuits 17 and 18. Tuned circuit 17 is connected across the output of source 10, and one terminal is grounded. Tuned circuit 18 is inductively coupled to tuned circuit 17, and a center tap 19 on the inductance 20 of tuned circuit 18 is grounded. By reason of the inductive coupling between the tuned circuits 17 and 18, the voltage across the terminals of the tuned circuit 18 differs by a quarter cycle from that across the terminals of the circuit 17. The voltages at the opposite terminals of the tuned circuit 18 are balanced with respect to ground by reason of the grounded center tap 19 of the inductance 20.

The first, or control, electrode 21 of device 11 is coupled through a condenser 22 to the upper terminal of the tuned circuit 18, and the first, or control, electrode 23 of device 13 is coupled through condenser 24 to the lower terminal of circuit 18. The oppositely phased voltages on the opposite terminals of tuned circuit 18 are accordingly impressed on the control electrodes 21 and 23. The first or control electrode 25 of device 12 is coupled through a condenser 26 to the ungrounded terminal of tuned circuit 17, and accordingly a voltage is impressed thereon which differs in phase by a quarter cycle from the oppositely phased voltages on the control electrodes 21 and 23.

These voltages are illustrated as vectors in Fig. 2, in which the vector E_{21} represents the voltage on the control electrode 21, the vector E_{23} represents the oppositely phased voltage on the control electrode 23, and the vector E_{25} represents the voltage on the control electrode 25 which differs by a quarter cycle from the voltages represented by vectors E_{21} and E_{23} .

While I have shown only one arrangement for impressing such variously phased voltages on the devices 11, 12 and 13, any suitable arrangement may be utilized, as, for example, that shown in the above mentioned application of George M. Brown. In such application the voltage to be applied to control electrode 25 is obtained by connecting across the tuned circuit 18 a path serially including a resistance and a condenser, the reactance of the condenser at the frequency of carrier wave from the source 10 being equal to the resistance. The condenser 26 couples the control electrode 25 to the point between the resistance and condenser and is energized with a voltage as represented by the vector E_{25} of Fig. 2.

Suitable operating potentials are supplied to the devices 11, 12 and 13 as follows. The cathodes 27, 28 and 29 of the devices 11, 12 and 13 are grounded. A resistance 30 is connected between the control electrode 21 and cathode 27. A resistance 31 is connected between control electrode 25 and cathode 28. A resistance 32 is connected between control electrode 23 and cathode 75

29. The anodes 40, 41 and 42 of the devices 11, 12 and 13 are connected together and through a tuned circuit including an inductance 43 and condenser 44 in shunt thereto, and an inductance 45, 5 to the positive terminal of a suitable source 46 of operating potential. The negative terminal of the source 46 is grounded, and a point between the inductances 45 and 43 is bypassed to ground through a condenser 47 so that the inductance 45 and condenser 47 act as a filter for continuous current flowing through the anodes of the devices 11, 12 and 13 from source 46.

The second, or screen, electrode 48 of the device 12 is connected to the cathode 28 through a bypassing condenser 49, and to the positive terminal of the source 46 through resistance 50. This condenser 49 has low reactance at the frequency of waves from source 10 but has high reactance at signal frequencies. The devices 11 and 13 are of the type having five control electrodes, of which the third may be used as a gain control electrode. Such third or gain control electrode 51 of the devices 11 is connected to one terminal of the secondary 52 of a transformer whose primary 53 is energized through an audio amplifier 54, through which signals from the microphone 16 are amplified. Such third or gain control electrode 55 of the device 13 is connected to the other terminal of the secondary 52, and the center tap 56 of the secondary 52 is connected to ground.

The second and fourth, or screen, electrodes 60 of the device 11 are connected to the cathode 27 through a condenser 61, and to the second and fourth, or screen, electrodes 62 of the device 13 and to the positive terminal of the source 46. If desired, a condenser 63 may be connected directly between the electrodes 62 and cathode 29.

With the operating circuits described, the operation is as follows. When there is no signal from the microphone 16, and the third control electrodes 51 and 55 of devices 11 and 13 are at ground potential, the three currents in the anodes 40, 41 and 42 are as illustrated by the vectors of Fig. 3. The current flowing through the anode 40 is controlled in intensity by the voltage on the control electrode 21, represented by vector E_{21} in Fig. 2, such current being represented by vector I_{40} in Fig. 3. For the sake of simplicity, only the alternating component of current in the anodes 40, 41 and 42 is considered in the vectors of Fig. 3. The current in the anode 41 of the device 12 is controlled by the voltage on the control electrode 25 and is represented by the vector I_{41} of Fig. 3. Similarly, the current in the anode 42 of the device 13 is represented by the vector I_{42} of Fig. 3 and is controlled by the voltage represented by vector E_{23} of Fig. 2 on control electrode 23.

While the phase of the three currents I_{40} , I_{41} and I_{42} is completely controlled by the control electrode voltages E_{21} , E_{23} and E_{25} respectively, the intensity of the currents I_{40} , I_{41} and I_{42} are not entirely dependent on the intensity of the control voltages E_{21} , E_{23} and E_{25} respectively. Since the control voltages E_{21} , E_{23} and E_{25} are constant, so far as these voltages are concerned, the currents I_{40} , I_{41} and I_{42} are constant. However, each of the devices 11 and 13 includes a gain control electrode, which is effective to control the amplification through the respective discharge device.

When modulating signals from the microphone

16 are transmitted through the amplifier 54 and appear in opposite phase on the gain control electrodes 51 and 55, the gain of the devices 11 and 13 varies oppositely, so that, when the current I_{40} increases, the current I_{42} decreases. Conversely, when the current I_{40} decreases, the current I_{42} increases.

When there is no signal from the microphone 16, the currents I_{40} and I_{42} are equal and in opposite phase and cancel, excitation of the tuned circuit 43, 44 being caused only by the current represented by vector I_{41} . When the signals from microphone 16 cause one of the currents I_{40} and I_{42} to increase and the other to decrease, these currents do not cancel out, and a resultant current remains, which combines with the current I_{42} to produce a resultant current of phase different from current I_{42} . This current flowing through the tuned circuit 43, 44 produces a voltage thereacross which is different from the voltage thereacross when only current I_{41} flows through the tuned circuit 43, 44.

This change in phase of the current I_{41} is illustrated in Fig. 4 for one particular instant at which signal potential from the microphone 16 is such that the gain control electrode 51 is positive with respect to ground and gain control electrode 55 is negative. At such instance the gain of the device 11 is increased, and the gain of the device 13 is decreased. Consequently, as illustrated in Fig. 4, the vector I_{40} is much larger than the vector I_{42} , and the three vectors I_{40} , I_{41} and I_{42} combine to form a resultant I_{43} , which represents the current flowing through the inductance 43. This current I_{43} leads the current I_{41} flowing through anode 41 of device 12 by an angle θ .

The vector difference, labelled $I_{40}-I_{42}$, is represented by the dotted line extending between the separated ends of the vectors I_{41} and I_{43} , and is proportional to the instantaneous intensity of the modulating signals from the microphone 16. It is evident from an inspection of Fig. 4 that incremental changes in the vector labelled $I_{40}-I_{42}$, which is proportional to the modulating potential, do not produce proportionate incremental changes in the angle θ . As set forth previously, such proportionality is necessary to avoid distortion caused by the production of harmonics and cross-modulation products thereof. Actually, the greater the angle θ , the less is the change in the angle θ produced by a unit change in the modulating potential.

As set forth in the above mentioned application of George M. Brown for Frequency modulation systems, a suitable reduction in the intensity of the current I_{41} made with every increase of the modulating potential is effective to increase the angle θ just sufficiently during each incremental change thereof to maintain substantial proportionality between changes of the angle θ and changes of intensity of the modulating potential. Now it is evident that, without such corrective reduction of the current I_{41} , the current I_{43} is greater than the current I_{41} . If the current I_{41} be reduced upon increases in the resultant current I_{43} by a suitable amount, a high degree of linearity may be obtained between the angle θ and the modulating potential which produces it.

Apparatus for causing the current I_{41} to be reduced in response to increases in the resultant current I_{43} is provided as follows. The cathode 70 of a diode discharge device 71 is connected through a load resistance 72 in shunt to a by-

6 passing condenser 73, whose reactance at the frequency of carrier waves from the source 10 is small but at the highest frequency of signals from the microphone 16 is relatively large. The anode 74 of the device 71 is connected through an inductance 75 to ground to provide a continuous path for continuous current through the device 71, and is coupled through a coupling condenser 76 to the anodes 40, 41, and 42 of the devices 11, 12 and 13. Consequently, a unidirectional voltage is produced across the resistance 72 which is proportional to the resultant intensity of the carrier wave across the tuned circuit 43, 44, and is accordingly proportional to the total current through that tuned circuit, represented by the vector I_{43} in Fig. 4.

19 The cathode 80 of a triode discharge device 81 is connected through a suitable vapor discharge device 82 to ground. The anode 83 of the device 81 is connected to the screen electrodes 48 of the device 12. The control electrode 84 of the device 81 is connected to a point between the cathode 70 of the diode rectifier 71 and resistance 72.

20 The vapor discharge device 82 is of that type across which the voltage is substantially constant throughout large changes of current therethrough. The magnitude of resistance 72 is such that the rectified voltage thereacross is of such magnitude as to cause the control electrode 84 of the device 81 to operate over a linear portion of its characteristics. That is, the voltage across the resistance 72 is less than the voltage across the vapor discharge device 82 by an amount such that the cathode 80 is always maintained positive with respect to the control electrode 84, but not so positive that the control electrode 84 approaches that voltage at which current flow through the device 81 is cut off.

25 40 The discharge device 81 together with the vapor discharge device 82 constitute a continuous potential amplifier which is effective to apply to the screen electrode 48 of device 12 amplified potential changes across the resistance 72.

45 Referring to Fig. 5 the operability of the scheme of reducing the current I_{41} in response to increases in intensity of current I_{43} to produce linearity between the angle θ and modulating potential is shown. In this figure, the current 50 I_{41} is plotted as an abscissa on an arbitrary scale, and the vector difference $I_{40}-I_{42}$, corresponding to modulating potential, is plotted as ordinates to the same scale. When a small modulating potential, sufficient to cause 0.1 unit difference 55 in the vectors I_{40} and I_{42} is present, the vector I_{43} is produced extending to point A, and making an angle of 0.1 radian with the vector I_{41} . At such small angles of phase shift, the relation between the angle and the modulating potential 60 is substantially linear.

65 When modulating potentials of higher intensity produce larger phase shift, such, for example, as a modulating potential effective to produce a difference between the currents I_{40} and I_{42} of 0.7 unit exists, the vector I_{43} extends to point B and is at an angle with vector I_{41} of 0.61 radian. It is thus evident that the angle between the vectors I_{43} and I_{41} is substantially less than 0.7 radian, which is the phase shift that should 70 be produced in response to a modulating potential corresponding to 0.7 unit of the vector difference $I_{40}-I_{42}$.

75 Now if the system including the rectifier 71 and amplifier 81 were effective to produce so much feedback that the intensity of the current

I_{43} flowing through the tuned circuit 43, 44 were reduced to the intensity of the current I_{41} , the vector I_{43} , as illustrated in Fig. 5, would extend to the point C and would make an angle with vector I_{41} of 0.77 radian. It is evident that so much reduction in the intensity of the current I_{43} is effective to increase the angle between the current I_{43} and the current I_{41} too much. The proper angle 0.7 radian corresponding to a modulating potential which produces 0.7 unit difference between the currents I_{40} and I_{42} , is produced by reducing the intensity of the vector I_{41} only enough to reduce the current I_{43} only partially toward the intensity of the current I_{41} . The vector I_{43} which extends to point D makes an angle of 0.7 radian with the vector I_{41} , the vector I_{41} having been reduced by the amount BD to cause the vector I_{43} to lie at such angle.

It has thus been demonstrated graphically by the aid of Fig. 5 that, at a particular intensity of the modulating potential, the feedback through the rectifier 11 and amplifier 81 may be so adjusted that that component of the carrier wave transmitted through device 12 may be reduced by an amount proportional to the increase in intensity of the resultant of the three components of the carrier wave transmitted through the devices 11, 12 and 13 to the tuned circuit 43, 44 so that the relation between the phase shift of the resultant carrier wave on the tuned circuit 43, 44 and the modulating potential producing it, is the same as the relationship between a certain small phase shift and the modulating potential producing it.

By reference to Fig. 6, it may be shown that the amount of feedback found to be desirable in Fig. 5 at one particular intensity of the modulating potential is effective to maintain a linear relationship over a large range of such intensity between modulating potential intensity and carrier wave phase shift. The abscissae and ordinates in Fig. 6 are similar to those in Fig. 5 and need not be further described. At twelve different intensities of the modulating potential, the largest being sufficient to cause a phase shift of the carrier wave in one direction of 1.2 radians, graphical solutions are found, utilizing the same proportionate amount of feedback shown to be necessary in Fig. 5, to determine the resultant phase angle and intensity of the current I_{43} in each of such twelve cases.

In each case the amount of reduction in the vector I_{41} which has been plotted is proportional to the amount by which the resulting vector I_{43} exceeds the vector I_{41} in its unmodulated intensity.

A typical construction is illustrative. At an ordinate value of 1.1 unit, the dotted line 90 represents the shift in phase of voltage across the tuned circuit 43, 44 which would be produced if no reduction in intensity of the current through discharge device 12 were caused. The solid line 91 is drawn at an angle with respect to the vector I_{41} corresponding to the modulating potential unit 1.1, that is, at an angle of 1.1 radians. The line 92 represents the reduction in intensity of the vector I_{41} necessary to shift the phase of the resultant carrier wave the desired increased amount to render it proportional to modulating potential intensity. The line 93 represents the amount by which the resultant carrier wave intensity exceeds the unmodulated intensity thereof, and also is proportional to the amount of reduction of the component of the carrier wave transmitted through device 12 and represented by vector I_{41} .

The point 94 represents the end of the carrier wave vector which actually results when that amount of feedback is used which was determined as desirable by the graphical analysis of Fig. 5. It should be noted that point 94 does not correspond to the intersection of the line 91, drawn at the desired phase angle, and the horizontal line at the unit intensity 1.1. The departure of point 94 from this intersection represents an increase in phase angle larger than that desired, and consequently represents distortion.

In Fig. 6 there is no such distortion observable at modulating potential unit intensities less than 0.9, and the distortion is slight even at the maximum intensity shown, which is 1.2.

In Fig. 7 there is illustrated a graph showing certain relations between modulation potential and the resultant phase shift in various types of phase modulation systems. Modulation potentials are plotted as abscissae, and the resultant phase shifts are plotted as ordinates. The dotted curve 100 is a straight line, and represents the desired ideal relation between modulation potential intensity and the resultant carrier wave phase shift. The downwardly drooping curve 101 represents the relation in a system in which the carrier wave intensity transmitted through device 12 of Fig. 1 is not modulated. It is evident that large departures from linearity are present in this system even at modulation potentials low enough to produce only small amounts of carrier wave phase shift, of the order of ten or fifteen degrees.

The curve 102, which departs slightly from the ideal curve 100 at its upper end, corresponds to the relation between modulation potential intensity and carrier wave phase shift obtained with the system illustrated in Fig. 1. It is evident that a high degree of linearity exists in this relation even at relatively large amounts of carrier wave phase shift, of the order of 60° in either direction.

The graphical analysis of Fig. 5 indicates that an optimum amount of feedback may be produced so as to obtain the linearity indicated by the curve 102 of Fig. 7. This optimum amount of feedback may be obtained in the apparatus of Fig. 1 by adjustment of the resistance 50. By adjustment of this resistance the gain of the amplifier 81 is adjusted to adjust the amount of gain in the feedback loop and consequently the amount of degenerative feedback. Of course, the gain of device 81 may be adjusted in any other convenient manner. This resistance 50 may be adjusted until it is observed by suitable means that the carrier wave phase shift is substantially proportional to modulating potential intensity.

The non-linear relation between anode current and control grid voltage which occurs in any triode or pentode electron discharge device may be utilized to minimize the deviation of the curve 102 in Fig. 7 from the straight line 100. It is well known that, as the control electrode of an electron discharge device becomes less negative or more positive with respect to the cathode, the anode current tends to reach a maximum value. That is, with this type of electron discharge device, there is a certain region within which the control electrode voltage may be varied to produce proportionate changes in anode current, but when the control electrode voltage is made less negative or more positive than voltages within such region, the changes in anode current are less than those experienced within

such regions for equal changes in control electrode voltage.

By adjusting all the operating conditions of the electron discharge device 81 so that the relation between its control electrode potential and anode current is linear so long as the discharge device 81 operates along that portion of the curve 102 which coincides with the straight line 100, and by making these conditions such that the amplification of the device 81 is reduced when its control electrode 84 reaches a less negative or more positive potential with respect to the cathode 80, so that the device 81 is operating along the upper portion of the curve 102 which does not coincide with straight line 100. The feedback may be reduced in any desired amount at times when the carrier wave is shifted a large amount in phase, so that the curve 102 of Fig. 7 is given any desired linearity.

In general, any discharge device may be operated under such conditions as to have the above described characteristics. However, it is desirable to use a discharge device whose cathode or filament is capable of emitting a relatively small discharge current. Uncoated tungsten filaments are of this type. The anode current and control electrode bias are adjusted so that saturation of the electron emission from the cathode 80 is approached for the apparatus of Fig. 1 where the apparatus of Fig. 1 begins to operate along that portion of the curve 102 of Fig. 7 which deviates from the straight line 100.

The same effect may be achieved by utilizing that portion of the control electrode voltage-anode current characteristic where the control electrode becomes sufficiently negative to approach anode current cutoff. In this region of that characteristic, equal reductions in anode current require larger and larger increases in negative control electrode potential. By the insertion of an additional continuous potential amplifier between the control electrode 84 of device 81 and resistance 12, and by making such additional discharge device operate with its control electrode becoming increasingly negative in potential as the carrier wave in the tuned circuit 43, 44 is increasingly shifted in phase the same result may be obtained. It is, of course, necessary to reverse the polarity of the diode rectifier 71 to obtain the correct polarity across resistance 12.

Where signal voltages from the microphone 16, or other source of signals, are transmitted through the amplifier 54 in equal intensity at all frequencies, the apparatus of Fig. 1 is very satisfactory, producing a phase shift of the carrier wave proportional to the intensity of signal voltage at any frequency. Consequently, the frequency of the carrier wave is modulated over a range which is proportional both to signal voltage intensity and frequency. Such transmission is desirable in certain applications since noise voltages are more objectionable at high frequencies, and the large frequency shift of the carrier wave obtained in response to high frequency signal voltages are effective in minimizing the effect of such noise voltages.

Where, as in the present standard frequency modulation broadcasting, it may be desired to obtain a frequency shift of the carrier wave which is substantially proportional to signal voltage intensity at all frequencies, it is necessary to modify the transmission of signals from the microphone 16 through the amplifier 54. To obtain in the apparatus of Fig. 1 a frequency

shift of the carrier wave which is proportional to signal intensity at any frequency, it is necessary to attenuate in the amplifier 54 signals from the microphone 16 an amount proportional to signal frequency. Generally this attenuation is made something less than proportional at high signal frequencies, so that high frequency signals are transmitted with somewhat greater intensity than lower frequency signals, the process being commonly called preemphasis, in order to obtain some high frequency noise suppression.

In any case, where signals from the microphone 16 are so attenuated as to produce substantially proportional frequency shift of the carrier wave in apparatus such as that shown in Fig. 1, the phase shift of the carrier wave produced by low frequency signals is much larger than the phase shift of the carrier waves produced by high frequency signals. In fact, where the carrier wave frequency shift is proportional to the original intensity of signals, the carrier wave phase shift is inversely proportional to signal frequency.

As a consequence, the amount of phase or frequency shift which can be produced by such an apparatus as that shown in Fig. 1 is limited by the maximum intensity of the lowest frequency signal to be transmitted. The phase shifts produced by the higher frequency components of signals from the microphone 16 are much smaller, and are substantially in linear relationship with the intensity of signals from the microphone 16, even without the feedback through the discharge device 81. Such feedback need not be used for such high frequency components of the signals.

In Fig. 8 I have shown a low pass filter to be inserted between the diode rectifier device 71 and the amplifier discharge device 81 for the purpose of minimizing feedback for such high frequency components. In this figure certain elements are identical with certain elements in the apparatus of Fig. 1, and are marked with like reference numerals. An inductance 110 is connected between the control electrode 84 of the device 81 and the upper terminal of the resistance 12 where it is connected to the cathode 70 of device 71. A condenser 111 is connected between the control electrode 84 and the lower terminal of the resistance 12, which is grounded. By its formation the filter including the inductance 110 and the condenser 111 may be recognized as a low pass filter, and its characteristics may be suitably adjusted by adjusting the values of the inductance 110 and condenser 111 so that it transmits voltages which appear across the resistance 12 and have frequencies corresponding to low frequency components of signals from the microphone 16. This filter, so adjusted, strongly attenuates higher frequency voltages which appear across the resistance 12, which voltages correspond to high frequency components of signals from the microphone 16.

By the use of this low pass filter, possible tendencies of the apparatus to "sing" or oscillate at certain frequencies are minimized.

The apparatus of Fig. 1 may be somewhat simplified if the gain of the discharge device 12 is adjusted over a sufficiently wide range by adjustment of the potential of the screen electrode 48. This simplification is illustrated by Fig. 9, in which only a portion of the apparatus of Fig. 1, thus simplified, is shown. In this figure certain elements are identical with certain elements of the apparatus of Fig. 1, and are marked with like reference numerals. The cathode 70 of discharge

device 71 is connected to the upper terminal of the inductance 43, that is, to the ungrounded or high frequency potential end of the tuned circuit 43, 44. The anode 74 of the device 71 is connected serially in order through the resistance 72 and condenser 76 to ground. The condenser 73 is connected in shunt to the resistance 72 to bypass high frequency currents therearound. A point between the resistance 72 and condenser 76 is connected to the positive terminal of source 46. An adjustable tap 112 on resistance 72 is connected through adjustable resistance 50 to the upper terminal of condenser 49 and thus to the screen electrode of device 12 of Fig. 1.

Carrier wave potentials appearing on the tuned circuit 43, 44 are impressed across the discharge device 71 and the load circuit therefor including resistance 72 and condenser 73, so that a continuous potential appears across the resistance 72, the intensity of this potential being proportional to the carrier wave intensity. A continuous current circuit for the diode 71 extends from the anode 74 through resistance 72, inductance 45 and inductance 43 back to the cathode 70.

Operating current for the screen electrode 48 is transmitted from the positive terminal of source 46 through resistance 72, adjustable tap 112, and resistance 50 to the screen electrode 48. The resistances 50 and 72, which are so connected that the operating current for the screen electrode 48 flows therethrough, must be so adjusted that, when no signal voltages are transmitted from the microphone 16, the screen electrode 48 is at the desired operating potential, so that discharge device 12 transmits the carrier wave to the tuned circuit 43, 44 in desired intensity.

Since the operating current for the screen electrode 48 flows through the resistance 72, it produces a unidirectional voltage thereacross, of such polarity as to prevent the discharge device 71 from conducting and from rectifying carrier wave potentials, unless such potentials exceed in peak value the unidirectional potential across the resistance 72 caused by the flow of operating current for screen electrode 48 therethrough. It is, therefore, necessary that the apparatus be arranged so that carrier wave potentials on the tuned circuit 43, 44 at all times exceed in peak intensity the unidirectional potential produced across resistance 72 by the flow of operating current for screen electrode 48 therethrough.

When the intensity of carrier wave potentials across the tuned circuit 43, 44 is varied as the phase of the carrier wave is varied in accordance with modulating signal potentials from microphone 16, the rectified unidirectional voltage across resistance 72 varies, so that the operating voltage of screen electrode 48 is reduced, thereby reducing the gain of discharge device 12, when the carrier wave potentials on tuned circuit 43, 44 increase. This result is the same as that obtained by the apparatus as shown in Fig. 1, and, provided that the gain of discharge device 12 may be sufficiently controlled by changes of operating potential of the screen electrode 48, a suitable amount of rectified unidirectional voltage may be taken from the resistance 72 by adjustment of the adjustable tap 112 thereof to produce the desired amount of feedback, in the same way as for the apparatus of Fig. 1. It must be remembered in connection with the apparatus of Fig. 9, that adjustment of the resistances 72 and 50 must be made simultaneously and oppositely in order to maintain the desired gain of the discharge device 12 when no signal is present.

In Fig. 10 there is illustrated an additional arrangement which may be substituted in the apparatus illustrated in Fig. 1 to influence the control electrode 48 in response to the intensity of carrier waves on the tuned circuit 43, 44. In this figure certain elements are identical with certain elements of the apparatus of Fig. 1, and are marked with like reference numerals. The electron discharge amplifier device 81, instead of being connected as a continuous potential amplifier as in Fig. 1, is capacity coupled so as to transmit alternating potentials down to very low frequencies. The cathode 80 of device 81 is connected to ground through a resistance 120 in shunt to which a bypassing condenser 121 is connected. The control electrode 84 is connected through a coupling condenser 122 to a point between the cathode 70 of diode rectifier 71 and resistance 72. The control electrode 84 is connected through a suitable resistance 123 to ground.

The device illustrated in Fig. 10 operates in much the same manner as that in Fig. 1, although it is preferred to use the device of Fig. 1. The reason is that the correcting potentials transferred to the screen electrode 48 of device 12 through the amplifier device 81 are essentially unidirectional pulses. The first few pulses may be transferred properly through the amplifier of Fig. 10 when transmission of signals is initiated, but as the condenser 122 charges up, the amplifier device 81 tends alternately to increase and decrease the intensity of that carrier wave component transmitted through device 12 above and below the value transmitted therethrough in the absence of a signal, instead of only reducing the value of that carrier wave component. However, reasonably good results may be attained with the apparatus shown in Fig. 10, even though a certain amount of amplified modulation of the carrier wave at syllable frequency results, and produces a slight dynamic modulation non-linearity. Normally, this is of little consequence.

Where a feedback arrangement is used according to my invention, the linear relationship between phase shift of the carrier wave and modulating signal intensity is so greatly improved that substantially perfect linearity obtains, even though the carrier wave phase be shifted as much as 60° in either direction. Phase shifts of the carrier wave which are substantially greater than this may be utilized if non-linearities no greater than those in previous systems be tolerated. With this high degree of linearity over such a large phase shift of the carrier wave, it is quite feasible to produce an excellent frequency modulated carrier wave without the enormous amounts of frequency multiplication heretofore necessary.

While I have shown and described a particular embodiment of my invention, it will be obvious to those skilled in the art that changes and modifications may be made without departing from my invention in its broader aspects and I, therefore, aim in the appended claims to cover all such changes and modifications as fall within the true spirit and scope of my invention.

What I claim as new and desire to secure by Letters Patent of the United States is:

1. In a system for modulating the phase of a carrier wave in linear relationship in accordance with a desired signal, the combination of means for modulating the time phase of said wave in accordance with a function of said signal, said means being effective to change the intensity of said wave as the time phase thereof is modulated, and means responsive to said change in intensity

of said carrier wave to modulate the time phase of said carrier wave further by such an amount that said time phase varies substantially according to a linear function of the intensity of said signal.

2. In a system for modulating the phase of a carrier wave in linear relationship in accordance with the desired signal, the combination of means for modulating the time phase of said wave in accordance with a function of said signal over a time approaching the time of a half cycle of said wave, said means being effective to increase the intensity of said wave as the time phase thereof is advanced or retarded and also being effective to modulate said time phase less than proportionately to the intensity of said signal, and means responsive to increased intensity of said carrier wave to increase said modulation of the time phase of said carrier wave to a linear relationship with the intensity of said signal.

3. In a system for modulating the phase of a carrier wave in linear relationship in accordance with a desired signal, the combination of means for generating two components of such a carrier wave, the time phase between said two components being substantially greater than zero and substantially less than one-half cycle, means for modulating the intensity of one of said components in accordance with such desired signal, means for combining said components after such modulation of one to produce a carrier wave whose phase is shifted in response to such desired signal, and means responsive to increases in the amplitude of such combined components for reducing the intensity of the other of said components.

4. In a system for modulating the phase of a carrier wave in linear relationship in accordance with the desired signal, the combination of means for generating two components of such a carrier wave, the time phase between said two components being substantially greater than zero and substantially less than a half cycle, means for modulating the intensity of one of said components in accordance with such desired signal, means for combining said components after such modulation of one to produce a carrier wave whose phase is shifted in response to such desired signal, means for detecting variations in intensity of such combined components for generating a continuous potential varying in accordance with a function of said signal, and means for reducing the intensity of the other of said components in accordance with said continuous potential.

5. In a system for modulating the phase of a carrier wave in linear relationship in accordance with the desired signal, the combination of means for modulating the time phase of said wave in accordance with a function of said signal, said means being effective to change the intensity of said wave as the time phase thereof is modulated, means for detecting changes in intensity of said wave for generating a continuous potential varying in accordance with a function of said signal, and means comprising an amplifier for said continuous potentials for modulating further the time phase of said carrier wave in accordance with said continuous potential in such amount that said time phase varies substantially according to a linear function of the intensity of said signal.

6. In a system for modulating the phase of a carrier wave in linear relationship in accordance with the desired signal, the combination of means

for modulating the time phase of said wave in accordance with the function of said signal, said means being effective to change the intensity of said wave as the time phase thereof is modulated, means responsive to changed intensity of said carrier wave to modulate the time phase of said carrier wave further in such amount that said time phase varies substantially according to a linear function of the intensity of said signal, and means for disabling said last means whenever the intensity and time phase of said wave are modulated by said first means in accordance with high frequency components of said signal.

7. In a system for modulating the phase of a carrier wave in linear relationship in accordance with a desired signal, the combination of means comprising a pair of electron discharge amplifier devices for generating separately two components of such a carrier wave, the time phase between said two components being substantially greater than zero and substantially less than a half cycle, means for varying the gain of a first amplifier device to modulate the intensity of one of said components in accordance with such desired signal, means for combining said components after such modulation of one to produce a carrier wave whose phase is shifted in response to such desired signal, means for detecting increases in intensity of said combined components for generating a continuous potential varying in accordance with a function of said signal, and means for impressing said continuous potential upon an electrode of the other amplifier device to vary its gain in such sense as to reduce the intensity of the other of said components in accordance with said continuous potential in such amount as to cause modulation of the time phase of said carrier wave to vary substantially according to a linear function of the intensity of said signal.

8. In a system for modulating the phase of a carrier wave in linear relationship in accordance with a desired signal, the combination of means for modulating the time phase of said wave in accordance with said signal, said means being effective to change the intensity of said wave as the time phase thereof is modulated, means for detecting changes in intensity of said wave for generating a continuous potential varying in accordance with a function of said signal, and means for further modulating the time phase of said carrier wave in accordance with said continuous potential by such amounts and in such sense that said time phase varies substantially according to a linear function of the intensity of said signal.

9. In a system for modulating the phase of a carrier wave in linear relationship in accordance with a desired signal, the combination of means for generating three components of such a carrier wave, two of said components being oppositely phased and the third being different by a quarter cycle in time phase from the other two, means for modulating oppositely the intensities of said other two components, means for combining said modulated components with said third component to produce a carrier wave whose phase is shifted less than proportionately to said signal, and means responsive to variations in intensity of said combined components for modulating the intensity of said third component in such sense and such amount as to produce a resultant phase shift of said combined component substantially proportional to the intensity of said signal.

WILLIAM F. GOETTER.
